UNITED STATES PATENT OFFICE.

HJALMAR CARLSON, OF DULUTH, MINNESOTA.

COMBINATION JACK AND PULLER.

Application filed March 15, 1926. Serial No. 94,641.

This invention relates to vehicle jacks and has particular reference to a jack for use upon automobiles.

The principal object of the invention is 5 to provide a jack for automobiles which may be operated by the vehicle engine.

Another object of the invention is to provide such a device which may be used for pulling the car out of the mud, or a hole.

10 A further object of the invention is the provision of a device of this character which may be comparatively simple and inexpensive to manufacture and applied to a vehicle as an accessory.

15 Other objects and advantages of the invention will appear in the further description of the invention.

Referring now to the accompanying drawing, forming part of this application, and 20 wherein like reference characters indicate like parts:

Figure 1 is a side elevation of the power unit of the device showing its application to the drive shaft of the vehicle to which 25 it is attached:

Figure 2 is a top plan view of the same;

Figure 3 is a side view of the anchoring means for the cable when the device is used as a puller;

30 Figure 4 shows one method by which the device may be used as a jack;

Figure 5 shows another method of jacking the car; and

Figure 6 is a view of one of the corner 35 brackets.

In the drawings, 1 represents the drive shaft of the vehicle to which are fixed two spaced bevel gears 2 and 3, they being oppositely disposed or facing each other. Directly beneath the shaft 1 is the bevel gear 4 fixed to one end of the stub shaft 5. The gear 4 is designed to mesh with either of the gears 2 or 3 as the case may be. Abutting the gear 4 and about the shaft 5 is the 40 spring housing 6, the shaft 5 being freely rotatable therein. Within the spring housing is a spiral spring, one end of which is attached to the shaft 5 and the other end fixed in any desired manner to the housing 6. The housing 6 is fixed to the rack 7 which has a hub 8 formed thereupon axially through which the shaft 5 extends. This 45 rack 7 is supported by a pair of longitudinal metal straps 10, spaced upon either side of the shaft 1, and a pair of transverse straps 11, the corners of the straps being riveted

or otherwise fixed together, forming a rectangularly shaped fabricated support, which is attached to the frame of the car in any desired manner and thereby held in fixed 60 rigid position. A metal saddle 12 is fixed to one face of each strap 11, within which saddles the rack 7 may reciprocate and moving with it everything through which the shaft 5 extends; this movement of the rack being 65 for the purpose of causing the gear 4 to mesh with either of the gears 2 or 3. To the bottom of the shaft 4 is fixed the winding drum 9 having the housing 13 thereabouts and adapted to revolve about the shaft 5 70 independently of the drum. The housing has a peripheral entrance 13 thereto through which the pulling cable 14 extends to its anchoring means. Since the housing rotates upon the shaft 5, the peripheral entrance 13 75 will always be in alignment with the cable 14. As a means for causing the rack 7 to reciprocate and thereby throwing the gear 4 in mesh with either of the gears 2 or 3, I have shown the pinion 15 held in any desired 80 manner in constant mesh with the rack. The pinion is fixed to the lower end of the operating rod, 16 which extends upwardly through the floor of the car and terminates in a handle portion 17' within convenient 85 reach of the driver of the vehicle. Thus by turning the handle 17' the pinion will cause the rack to reciprocate, throw the gears in mesh, and when the engine is started it will 90 revolve the winding drum 9 pulling in the cable 14.

When the device is used as a puller, I have shown as an anchoring means a corrugated stake 16 which may be driven into the ground and the projecting end made secure to the 95 free end of the cable 14. When thus applied the winding of the drum 9 will, of course, draw the car to the stake. If necessary the stake may be braced as shown in Figure 3 by a short length of lever 17 one end of which 100 is in the form of a yoke which bears against the stake 16 and the other end may rest against another stake 18 driven into the ground.

In Figure 4 the device is shown as applicable to a jack and in this modification the stake 16 is placed flat against the surface of the ground. The yoked end of the lever 17 is placed up against the axle 18 of the car adjacent the wheel to be raised and the other 110 forked end of the lever extends within a pair of suitably spaced holes 19 in the stake 16.

Thus when the cable 14 is applied to the forked end of the lever 17, and the car started thereby winding the cable, if the car has not lost its traction it will move forwardly until 5 the lever 17 is in a vertical position when the power is thrown out, leaving the wheel jacked. If it so happens that the car has no traction when it is desired to so jack up the wheel, when the drum winds the cable 10 14 it will pull the stake 16 along the surface of the ground, thereby raising the axle. It will be noted that the forked end of the lever 17 is so constructed that when the same reaches a vertical position the cable 14 will 15 slip therefrom which insures that the same will not pull too long.

In Figure 5 another method of jacking up a wheel is illustrated and in this method the point of the stake 16 is made to engage the 20 ground under the axle and the other end brought up against the bumper 20 of the car, when the hook 21 on the end of the line 14 is placed over the upper end of the stake as illustrated. Thus when power is exerted 25 upon the cable 14 it will straighten out, thereby raising the wheel.

Obviously when the gears are in neutral position and the cable 14 is freed the spring in the housing will cause the cable drum to 30 wind up the cable, and to make the same easily accessible when needed I have provided in either corner of the car a bracket 35 22, (Figure 6) which may be of any shape desired, and through any one of which the cable may pass to its anchoring means. With the cable 14 there will be provided a cord one end of which may be secured to the hook 21 and the other end to either of the brackets 22 so that when the cable is 40 completely wound upon its drum the cord may

be pulled which in turn will pull out the cable which then may be used for any desired purpose.

From the foregoing it is evident that I have provided an efficient, practical, combination jack and puller, and one that may be cheaply manufactured and easily installed.

It will of course be obvious to those versed in the art that when strain is exerted upon the cable 14 in either longitudinal direction it will hold the gear 4 in mesh with either of the gears 2 or 3 and the harder the pull the more secure will be the meshed engagement of the gears. Also the gears 2 and 3 55 are spaced far enough apart upon the drive shaft 1 to permit of the latter reciprocating vertically when the gears are in neutral and the automobile moving as common.

When the device is used as a jack as illustrated in Figure 5, the pulling in of the cable 14, tending to straighten the same, will also raise the stake 16 to a vertical position which will also aid in jacking the axle.

Having thus described my invention, what I claim and desire to secure by Letters Patent, is:

A pulling device of the character described comprising a driving shaft carrying spaced gears thereupon, a shaft carrying a drum and gear the latter optionally engageable with either of the spaced gears, a pulling cable about the drum and extendible in opposite directions, and means whereby the pull exerted upon the cable when the device is in action will hold the cooperative gears in mesh.

In testimony whereof I hereunto affix my signature.

HJALMAR CARLSON.
